COVER OPERATING MECHANISM FOR CUPOLA CHARGING APPARATUS

Harold W. Schwengel, Port Washington, Wis., assignor to Modern Equipment Company, Port Washington, Wis., a corporation of Wisconsin

Application March 28, 1952, Serial No. 279,027

6 Claims. (Cl. 214—19)

This invention relates to improvements in cover operating mechanism for cupola charging apparatus.

In my copending application for patent, Serial No. 279,877, filed April 1, 1952, an improved type of cupola and charging apparatus therefor is shown and described. This cupola is of the sealed type, and has means cooperable with an improved form of charging bucket for charging the cupola without changing the sealed condition of the cupola. In the structure shown in this application a cover is lowered onto the top of the charging bucket after the bucket is in charging position on top of the cupola. This cover is raised and lowered by means of cables and a power driven hoisting drum located above the cupola.

It is a general object of the present invention to provide an improved cupola charging apparatus wherein a cover is applied to and removed from the cupola charging bucket without requiring any special power driven equipment for this purpose.

A further object of the invention is to provide an improved cupola charging apparatus of the class described wherein the bucket cover is automatically applied to the bucket as the bucket moves toward cupola charging position, and is automatically removed from the bucket as the bucket is returning to the loading station.

A further object of the invention is to provide an improved cupola charging apparatus of the class described wherein the charging bucket cover is normally supported in a horizontal position in the path of the bucket as the latter moves vertically from the loading station toward cupola charging position; the bucket being movable upwardly into engagement with the underside of the cover, to carry said cover therewith to the loading station, and said cover being replaced on said supports as the bucket returns to the loading station.

A further object of the invention is to provide an improved cupola charging apparatus of the class described which is relatively simple in construction, inexpensive to manufacture, and otherwise well adapted for the purposes described.

With the above and other objects in view, the invention consists of the improved cupola charging apparatus, and all of its parts and combinations, as set forth in the claims, and all equivalents thereof.

In the drawing accompanying and forming a part of this specification, wherein one complete embodiment of the preferred form of the invention is shown, and wherein like characters of reference indicate the same parts in all of the view:

Fig. 1 is a side elevational view showing the improved cupola charging apparatus associated with a cupola;

Fig. 2 is an enlarged sectional plan view taken approximately along the line 2—2 of Fig. 1; and

Fig. 3 is a fragmentary vertical sectional view of the improved bucket cover and a portion of the charging bucket, taken approximately along the line 3—3.

Referring more particularly to the drawings, the numeral 10 indicates a cupola which may be of the sealed type such as that shown and described in my copending application above referred to. A skip carriage track 11 extends from a position above the upper end of the cupola 10, downwardly and laterally under a lime stone and coke weigh hopper 12 and under an iron weigh hopper 13. A skip carriage 14 is positioned to traverse the track 11 and pivotally supports a cupola charging bucket 15, being operable to move the latter between a cupola charging position indicated by the letter A, and

2

shown in dot and dash lines, and a bucket loading position shown at C and also indicated by dot and dash lines. The track 11 has an intermediate, vertically extending portion 16 which causes the bucket 15 and carriage 14 to travel vertically as said portion is traversed by the carriage 14. The structure of the skip carriage 14 and of the bucket 15 may be substantially identical with that shown in my copending application, Serial No. 279,877, and will, therefore, not be described in detail herein.

The skip carriage track 11 is supported by suitable framework, as shown, and this framework may include a pair of parallel beams 17 and 18 which are preferably connected to the outer sides of the tracks 11 as shown in Fig. 2. Positioned on and extending transversely between the beams 17 and 18 is a pair of parallel beams 19 and 20 which may be Z-shaped in cross-section and which may be provided with supporting gussets 19' and 20' respectively. The beams 19 and 20 are positioned on diametrically opposite sides of the path of movement of the bucket, and it will be noted that the beams 19 and 20 are so positioned with respect to the portion 16 of the track 11, that the bucket 15 travels vertically as it passes between said beams.

A bucket cover 21, which may be rectangular in shape, has a length greater than the spacing between the beams 19 and 20 and is also greater than the outer diameter of the bucket 15. The cover 21 has a transverse dimension not substantially greater than the outer diameter of the bucket 15, as shown in Fig. 2. The underside of the cover 21 is formed with a circular recess 22 which preferably has tapered marginal walls 23. The diameter of the marginal wall of the recess 22 is preferably substantially equal to the diameter of the upper end of the bucket 15 as shown in Fig. 3.

A pair of hoisting cables 24 is connected at one end to a pair of power driven cable drums 25 mounted above the upper end of the track 11, and at the other end to a rear end portion of the skip carriage 14. This connection may be of the same type as that shown in my copending application, Serial No. 279,877.

In the operation of the improved cupola charging apparatus, the cover 21 is normally positioned on the beams 19 and 20 in the manner shown in Figs. 1 and 2. With the skip carriage 14 and bucket 15 at the position C, a predetermined weight of iron is dumped into the bucket from the iron weigh hopper 13. The drums 25 are then rotated in a direction to pull the skip carriage 14 along the track 11 until the bucket 15 is directly below the limestone and coke weigh hopper 12. Here a predetermined weight of material is dropped into the bucket 15 from the weigh hopper 12. The hoisting drums 25 are then further rotated to pull the skip carriage 14 and the loaded bucket 15 upwardly toward cupola charging position A.

As the bucket 15 moves vertically upwardly through the position B, the upper end of the bucket 15 moves into the recess 22 on the underside of the cover 21 and said upper end is thus closed by the cover 21. The tapered or conical side wall 23 of the recess 22 automatically centers the cover 21 on the bucket 15. As the bucket moves upwardly from the position B toward the position A, it lifts the cover 21 off of the beams 19 and 20 and carries said cover with it to the position A as shown. The cover 21 remains on the bucket 15 while the contents of the bucket 15 is being emptied into the cupola, thus maintaining the upper end of the bucket in sealed condition during the cupola charging operation. As the skip carriage 14 is returning with the empty bucket 15 from the cupola charging position A to loading position C, the bucket 15 moves vertically downwardly through the position B. As the bucket thus moves, the ends of the cover 21 are replaced on the beams 19 and 20 as shown in Figs. 1 and 2.

The improved cupola charging apparatus provides a cover which efficiently seals the cupola charging bucket. In addition, special power driven mechanism for handling the cover is not required. The application of the cover to the bucket and its removal therefrom is accomplished automatically, and is governed solely by move-

ment of the bucket toward and away from cupola charging position.

Various changes and modifications may be made without departing from the spirit of the invention, and all of such changes are contemplated as may come within the scope of the claims.

What I claim is:

1. In combination: a cupola charging bucket having an open top; means including a track and a bucket carriage movable thereon for moving said bucket from a bucket loading position to a cupola charging position, said movement including upward travel of the bucket, a loose bucket cover having a length greater than the outer diameter of said bucket; and a pair of spaced fixed supports intermediate said loading position and charging position located on opposite sides of the path of travel of said bucket and normally supporting the opposite ends of said cover from beneath against downward movement by gravity when said bucket is in loading position, said cover being disposed horizontally on said supports and being positioned for engagement by the open top of said bucket to be lifted off of the supports by the bucket and carried thereby to the charging position, said supports being also positioned to intercept said cover during return travel of the bucket toward loading position to prevent further movement of the cover with the bucket.

2. In combination: a cupola charging bucket having an open top and having a pair of coaxial trunnions; means including a skip carriage having bearings in which said trunnions are journaled for moving said bucket from a bucket loading position to a cupola charging position, said movement including upward travel of the bucket and skip carriage, a loose bucket cover having a length greater than the outer diameter of said bucket; and a pair of spaced supports intermediate said loading position and charging position located on opposite sides of the path of travel of said bucket and positioned to normally support the opposite ends of said cover from below against downward movement by gravity when said bucket is in loading position, said cover being disposed horizontally on said supports with its longitudinal dimension normal to said trunnion axes, and said cover being positioned for engagement by the top of said bucket to be lifted thereby off of the supports and thereafter carried to the charging position, said supports being also positioned to intercept said cover during return travel of the bucket toward loading position to prevent further movement of the cover with the bucket.

3. In combination, a cupola charging bucket, means supporting said bucket for movement between loading and charging positions, said bucket having an open top, a loose bucket cover, a stationary cover support intermediate the length of the path of movement of the bucket, said cover having portions which project beyond the bucket and which are positioned to be engaged by said cover support as the bucket moves past said support toward loading position to thereby remove the cover from

the bucket and hold the latter while the bucket is being loaded, said support being positioned so that return movement of the bucket from loading position past the support causes replacement of the cover on the bucket and simultaneous removal from the support.

4. In combination, a cupola charging bucket, means supporting said bucket for movement in a generally up and down direction between charging and loading positions, said bucket having an open top, a loose bucket cover, a stationary cover support intermediate the length of the path of movement of the bucket, said cover having portions which project beyond the bucket and which are positioned to be engaged from beneath by the cover support as the bucket moves downwardly past said support toward loading position to thereby remove the cover from the bucket and hold the latter while the bucket is being loaded, said support being positioned so that upward movement of the bucket from loading position past the support causes replacement of the cover on the bucket and simultaneous lifting of the cover off of the support.

5. In combination, a track, a carriage movable on said track between a loading position and a charging position, a cupola charging bucket supported on said carriage, said bucket having an open top, a loose bucket cover, a cover support intermediate the length of said track, said cover having portions which project beyond the bucket and which are positioned to be engaged by said cover support as the bucket moves past said support toward loading position to thereby remove the cover from the bucket and support the latter while the bucket is being loaded, said support being positioned so that return movement of the bucket from loading position past the support causes replacement of the cover on the bucket and simultaneous removal from the support.

6. In combination, an inclined track, a carriage movable on said track between a charging position and a loading position, a cupola charging bucket supported on said carriage, said bucket having an open top, a loose bucket cover, cover supporting means intermediate the length of said track, said cover having portions which project beyond the bucket and which are positioned to be engaged from beneath by said cover supporting means as the carriage moves the bucket past said support toward loading position to thereby remove the cover from the bucket and hold the latter while the bucket is being loaded, said cover supporting means being positioned so that upward return movement of the carriage and bucket from loading position past the support causes replacement of the cover on the bucket and simultaneous removal from the support.
